UNITED STATES PATENT OFFICE.

ALFRED W. MURDOCK, OF NEW YORK, N. Y., AND ARTHUR J. DOUGHERTY, JR., OF WEST NEW YORK, NEW JERSEY.

DESIGN FOR A DISPLAY-CABINET.

47,776.

Specification for Design.

Patented Aug. 31, 1915.

Application filed April 12, 1915. Serial No. 20,969. Term of patent 3½ years.

To all whom it may concern:

Be it known that we, ALFRED W. MURDOCK and ARTHUR J. DOUGHERTY, Jr., citizens of the United States, and residents of the borough of Manhattan, in the county of New York, State of New York, and West New York, Hudson county, State of New Jersey, respectively, have invented a new, original, and ornamental Design for Display Cabinets, of which the following is a specification, reference being had to the accompanying drawing, forming part thereof.

Figure 1 is a plan view of a display cabinet showing our new design, and Fig. 2 is an edge view thereof.

We claim:

The ornamental design for a display cabinet, as shown.

ALFRED W. MURDOCK.

ARTHUR J. DOUGHERTY, JR.
